JOSEPH F. BABITT, OF WELLINGTON, OHIO

SAFETY DEVICE FOR LADDERS

Application filed August 20, 1931. Serial No. 558,242.

My invention relates to safety device for ladders, and more especially fire ladders.

One object of my invention is to provide a device that is readily adjusted and ensures a safe hold on any surface.

Another object is to provide a safety lock for the pronged foot when the ladder is not in use.

Other objects and advantages will be apparent from the following description in connection with the accompanying drawings, and in which:

Figure 1 is a perspective view of a fragment of a ladder with the safety device in holding position; Fig. 2 is a side elevation with the device in holding position; Fig. 3 is an opposite side elevation similar to Fig. 2; Fig. 4 is similar to Fig. 2, with the safety device closed; Fig. 5 is a rear elevation with the safety device closed; Fig. 6 is a longitudinal section taken on line 6—6 of Fig. 3, with the stile broken away; Fig. 7 is a side elevation of the end of the ladder stile; Fig. 8 is a front elevation of the device; Fig. 9 is a perspective view of the safety foot of the device; Figs. 10 and 11 are perspective views of the parts that compose the metal box, and Fig. 12 is a perspective view of the pivoted safety foot holder.

Referring specifically to the drawings: the numeral 10 refers to the ladder stile with rungs 11; a metal box or casing which consists of two opposite parts or sides 13 and 14 with connecting plates 15 and 16, is bolted to the base of the stile which conforms to the inner contour of the metal box, into which it fits.

The safety foot holder 17 is in one piece, which is bent to form a pair of side cheeks 18 and 19 at its upper end and a pair of opposite clamping flanges 20 and 21 at its lower end. Said cheek 19 has a curved top with the body tapered inward towards the bend line of the flange, while said cheek 18 has a semi-circular top with a projection 18a, extending therefrom, the body of the cheek 18 being straight and at a right angle to the face of the safety foot holder 17.

The clamp flanges 20 and 21 of the safety foot holder 17 retain the safety foot 22

within the recess 23, formed between the inner walls of the safety foot holder 17 and the clamp flanges 20 and 21, by means of bolts 24 and 25 turned through the apertures 26 and 27 in the safety foot 22, said safety foot having projecting shoulders 28 and 29 extending at right angles to the edges which prevent the foot sliding up too far within the recess 23. The safety foot 22 terminates in a plurality of wedge-shaped prongs or toes 30, and the point or edge of said prongs pressing down upon any surface, prevents slipping.

The cheeks 18 and 19 are pivoted upon the bolt 31 which is mounted through the bearing 32 within the stile 10, and the head of said bolt presses the lock washer 31a against the outside surface of the cheek 19 when the bolt is screwed into the aperture 33 in the cheek 18.

A compression spring 34 is attached to the inner surface of the safety foot holder 17 by a pin 34a, said spring projecting through the metal box and into the stile 10 at an angle.

A round head 36 through which a ring 37 is mounted is screwed upon a threaded bolt shank 35 after the said shank has been thrust through the bearing 39 and the spring 60. The enlarged bolt end 38 projects through said bearing 39 and being larger in diameter than the shank 35 prevents said bolt end 38 from slipping out as the ring 37 draws the bolt back through the aperture 40 in the arm 18, and away from the surface of the plate 50 attached to the outer surface of the metal box. This allows the safety foot holder 17 to be pressed back, flat against the end surface of the metal box, when the lock or latch 41 is drawn down by means of the ring 42 in the pin 43 mounted on the under side of the lock 41, said lock being hinged at 44 to the base of the metal box.

A compression spring 45 is mounted within the aperture 49 and on the bolt 46 which passes thru openings in the lock and in the metal casing. This spring is adapted to expand between the washer 47 and burr 48 at one end and the inside of the metal casting at the other end, thus tending to keep

the lock 41 in contact with the bottom side of the metal casing.

When the ring 42 is drawn down, opening the lock 41, the prongs 30 of the safety foot 5 22 may be pushed back into a perpendicular position and the ring 42 released, and then the lock clamps down on the ends of the prongs 30 which then rest within the lock, the sharp edges of the prongs being concealed in this way to prevent injury in handling.

A lock pin 51 with rounded end 52 projects through the aperture 53 in the metal box and terminates in an elongated head 54. 15 The end 52 presses into a depression 55 in the stile 10, which prevents the pin 51 from sliding back and forth. When the safety foot holder is flat against the surface of the metal box an additional safety lock is secured by turning the elongated head 54 of the pin 51 at right angles after it passes through the slot 56 in the circular depression 57 in the safety foot holder 17.

A fire ladder equipped with this device 25 at both ends of each ladder stile saves time in erecting as either end of the ladder may be used with equal security.

In use, the safety foot 17 may be swung out by releasing or opening the latch 41, to 30 allow the prongs 30 to engage the floor or ground and so hold the ladder against slipping. Reverse action permits the foot 17 to be swung in and held by engagement with the latch 41.

35 I claim:

1. A safety device for ladders, comprising a casing fixed to the end of the ladder stile, a holding foot pivoted to the casing, and a latch pivoted to the casing and engageable 40 over the toe of the foot when the latter is swung in to closed position.

2. A safety device for ladders as in claim 1, and a spring pin mounted in the casing and engageable with the foot when the 45 latter is swung out, to hold the same in open position.

3. A safety device for ladders as in claim 1, and a spring between the casing and foot, tending to swing the latter to open position.

50 4. A safety device for ladders as in claim 1, and a spring between the casing and the latch tending to hold the latter closed over the toe of the foot.

55 5. A safety device for ladders as in claim 1, the casing comprising a box fitting over and enclosing the end of the stile.

60 6. A safety device for ladders as in claim 1, the foot having flanges at opposite sides of the casing, and a spring pin mounted in the casing and movable transversely therein to engage or disengage one of the flanges.

65 7. A safety device for ladders as in claim 1, the casing enclosing the lower end of the stile, and the latch being hinged to the lower

end of the casing, to engage or release the toe of the foot.

In testimony whereof, I do affix my signature.

JOSEPH F. BABITT.
